CORNER SHELF

Eric W. Anderson, Chicago, Ill.

Application September 7, 1935, Serial No. 39,517

4 Claims. (Cl. 211—90)

This invention relates in general to a corner shelf and holder preferably formed of sheet metal and attachable in an angular corner of a room, a cupboard, and the like.

5 An important object of the invention is in the provision of a corner shelf made entirely of sheet metal and having strengthening ledges for supporting the shelf and attaching it to a wall or other surface.

10 A further object of the invention is in the provision of improved means for attaching a shelf of this kind to a wall and for holding the attaching means in place.

A still further object of the invention is in the 15 provision of hooks formed of the material of the shelf or separately formed and attached thereto for suspending articles such as cups or suspending kitchen utensils therefrom.

A still further object of the invention is in the 20 provision of brackets formed out of the material of the shelf and bent downwardly therefrom or attached to the shelf for supporting a rail or rod upon which articles such as a drying cloth may be hung.

25 Other objects of the invention will hereinafter appear, the preferred structures being shown in the accompanying drawing in which,

Fig. 1 is a top view of a shelf in accordance with this invention as applied to an angular recess;

Fig. 2 is a front view of the shelf;

Fig. 3 is a section taken on the line 3—3 of Fig. 1;

Fig. 4 is a section taken on the line 4—4 of Fig. 1;

Fig. 5 is a view of the under side of a shelf in which the hooks and fastening means are secured thereto by spot-welding;

Fig. 6 is a section taken on the line 6—6 of Fig. 5; and

Fig. 7 is a section taken on the line 7—7 of Fig. 5.

A number of inexpensive sheet metal shelf structures have been provided for attachment to 45 a plane wall of a straight vertical surface but the provision of a shelf of this kind for an angular corner involves different details of construction and requires different means for attaching the shelf in place. The present invention provides a simple and inexpensive shelf which is made of sheet metal either by punching and forming a blank of sheet metal to provide the necessary hooks and attachment lugs, or by providing additional parts which are soldered, spot-

welded or otherwise secured to the main portion of the shelf.

Referring now more particularly to the drawing, a shelf 10 is formed of a blank of sheet material with its rear or side edges 11 bent downwardly to fit an angular recess 12 of a wall, a cupboard, or any other surface in which an additional shelf or support is desirable. At the front the edge 13 is turned upwardly and then bent downwardly upon itself to provide a 10 strengthening rib or rail at the front of the shelf which gives the shelf the appearance of thickness when viewed from the front, provides a rail for retaining articles on the shelf, and materially strengthens the shelf transversely. 15

Along the front edge of the shelf tongues 14 of metal are cut out by forming openings 15 therein, and the tongues are bent downwardly and forwardly to form hooks 16 upon which dishes, cooking utensils or other articles may be suspended as desired. When used for hooks the tongues are usually turned forwardly as shown and in this position a cross bar or rod may be supported between them; or some of the hooks may be bent rearwardly for supporting a rod 25 therein as shown in Figs. 5 and 6.

In order to secure the shelf to the sides of the wall or recess, lugs 17 are punched out of the material of the shelf and bent downwardly parallel to but spaced from the downwardly turned 30 edges thereof. These lugs and the adjacent edges are provided with registering perforations 18 and 19 respectively through which a fastening nail 20 is inserted. This nail is guided by the openings 18 and 19 so that it will extend straight 35 into the wall and if pressed or hammered in place the lug 17 is bent slightly as shown more clearly in Fig. 4, which binds and therefore holds the nail more tightly in place so that it will not easily become dislodged from the wall or from 40 the shelf, thereby holding the shelf securely in place so that it is not easily or accidentally dislodged.

Instead of making the hooks and lugs out of the material of the shelf itself, hooks 21 may be 45 attached to or form a part of a bar 22 which is attached to the under side of a shelf 23 by soldering or spot-welding 24. Lugs 25 may also be separately secured to the under side of the shelf in proper spaced relation to the edges 50 thereof by an angular portion 26 which is spot-welded to the under side of the shelf.

In this form of the shelf a bracket 27 may be secured at the sides having a depending portion in which is an outwardly pressed cup 28 for re- 55

ceiving therebetween a rod 29 or a bracket of this kind may be pressed out of the material of the shelf and bent downwardly to support the rod for holding articles thereon.

5 In the constructions above shown the rear-most tip or angular corner of the shelf is omitted, leaving a blunt end 30 which does not fit closely into the angle between the walls. The reason for this is that in most angular constructions, 10 whether walls or other similarly related surfaces, the corner itself is not exact, or it is filled with 15 bumps or projections which would prevent the shelf from fitting closely therein and therefore one of the sides of the shelf would not fit tightly against the wall. By leaving this space at the 20 rear the angular corner is not exactly filled but the sides will still fit tightly against the wall and the fastening means may therefore be properly applied to the side walls for holding the shelf 25 more firmly and neatly in place. By tapping the fastening nails and the lugs 17 so that the latter are slightly bent, the nails are held in place so that they are not easily disengaged without first straightening the tabs parallel with the bent edges 11. Shelves of this kind are easily applied and removed and will hold a considerable weight both upon the shelf and suspended from it as set forth.

I claim:

1. A triangular metal shelf having integral downwardly turned sides and fastening lugs spaced from but parallel to the sides, the lugs and the sides opposite them having perforations for receiving and guiding fastening means inserted therethrough into a wall. 5

2. A structure in accordance with claim 1, in which the lugs are bendable out of parallel with the corresponding sides to grip a fastening means inserted therethrough and hold it yieldingly in 10 place.

3. In a triangular sheet metal shelf structure, downwardly turned sides with perforations and a front strengthening flange, means insertable into adjacent walls to uphold the shelf, a plurality of 15 tongues formed from the material of the shelf and bent downwardly below the shelf adjacent the flange to provide supporting hooks.

4. In a triangular metal corner shelf, a metal sheet having integral downwardly turned side 20 flanges with spaced perforations therein, integral bendable lugs projecting below the sheet parallel to the flanges having perforations registering with those of the flanges, and fastening nails insertable through the perforations of the lugs and flanges and into side walls for supporting the shelf, the insertion of the nails and bending of the lugs thereby binding the nails in place. 25

ERIC W. ANDERSON.
